UNITED STATES PATENT OFFICE.

GEORGE W. DRESS AND CHRISTIAN F. BECK, OF STEELTON, PENNSYLVANIA.

T-RAIL.

1,034,428.

Specification of Letters Patent.

Patented Aug. 6, 1912.

Application filed October 6, 1911. Serial No. 653,979.

To all whom it may concern:

Be it known that we, GEORGE W. DRESS and CHRISTIAN F. BECK, citizens of the United States, residing each at Steelton, in the county of Dauphin and State of Pennsylvania, have invented a new and useful Improvement in T-Rails, of which the following is a specification.

The present invention aims to provide, in a rail having a removable tread, a novel means for holding the tread upon the rail, and to provide novel means for reinforcing the rail at the joint between the body members, the said reinforcing means serving also to hold the tread in place upon the body members.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—Figure 1 shows the invention in perspective; Fig. 2 is a side elevation at the joint between the body members; Fig. 3 is a side elevation at the joint between the tread members; Fig. 4 is a section on the line 4—4 of Fig. 3; and Fig. 5 is a section on the line 5—5 of Fig. 2.

In carrying out the invention there is provided a pair of body members 1, the joint between which is denoted by the numeral 2. Supported by the body members 1 and extended across the joint 2 is a body member 3, the joint between adjacent body members 40 being denoted by the numeral 4. Each body member 1 includes a web 5, a base flange 6, and a ball 7, located upon one side only of each tread member. In the inner face of the ball 7 there is a recess 8, and overhanging the recess 8 is a rib 9.

The invention further includes a primary splice bar denoted by the numeral 10, and an oppositely disposed, secondary splice bar denoted by the numeral 11. The primary splice bar 10 is fashioned along its upper edge, and upon its inner face with an inwardly projecting rib 12, below which is a rib 14, there being a recess 15 between the ribs 12 and 14. The secondary splice bar 11 is engaged along its upper edge with the under faces of the balls 7 of the body

members 1, it being understood, of course, that the splice bars 10 and 11 extend across the joint 2 between the body members 1. Both of the splice bars 10 and 11 are laterally prolonged, as indicated at 17, to lie along the upper faces of the base flanges 6 of the body members 1, the parts 17 terminating in depending side members 18 extended across the longitudinal edges of the base flanges 6, the parts 18 terminating in extensions 19 prolonged below the lower faces of the body members 1, the extensions 19 terminating in approaching feet 20 extended beneath the base flanges 6 of the body members 1.

Located between the adjacent primary splice bars 10 are grip bars 21 provided with spaced ribs 22 and 23, defining a recess 24 between them. Each grip bar 21 is equipped with a laterally extended foot 25 terminating short of the outer edge of the base flange 6 of the body member 1 to which the grip bar 21 is applied.

Securing elements, preferably taking the form of bolt and nut structures 26 extend through the primary splice bars 10, through the secondary splice bars 11, and through the webs 5 of the body members 1, upon both sides of the joint 2 between the body members 1. Other bolt and nut connections 27 extend through the parts 19 and 20 of the splice bars 10 and 11, the elements 27 being located below the base flanges 6 of the body members 1. At this place it may be noted, referring particularly to Fig. 2, that the parts 19 and 20 are located at the terminal portions only of the body members 1, adjacent the joint 2. The grip bars 21 are secured to the web 5 of each body member 1 by means of bolt and nut connections 28. The tread members 3 comprise a ball 29, a web 30 and a flange 31.

In practical operation, the tread member 3 is mounted in place upon the body members 1, to extend across the joint 2 therebetween, one of the flanges 31 of the tread member 3 being engaged by the rib 9 of the ball 7, the other flange 31 of the tread member 3 being engaged by the flange 22 of the grip bar 21 and by the flange or rib 12 of the primary splice bar 10. The rib 23 of the grip bar 21 engages beneath the walls of the body members 1, and the rib 14 of the primary splice bar 10 is similarly engaged. The feet 20 of the splice bars 10 and 11 engage beneath the base flanges 6 of the body members 1,

the upper edge of the splice bar 11 engaging beneath the ball 8, as shown most clearly in Fig. 5. It will be understood readily, referring to Fig. 2, that the parts 19, which 5 coöperate with the parts 20 of the splice bars 10 and 11, serve to reinforce the body members 1 at the joint 2. The tread members 3 are preferably fashioned from harder material than the body members 1, to withstand 10 wear, and owing to the fact that the tread members 3 are symmetrical, they may be turned end for end, readily, so that wear may be compensated for.

The device is simple in construction and 15 of few parts, and the several elements of the constituent parts coöperate at once, to hold the tread 3 in place, and to reinforce the device at the joint.

Having thus described the invention, what 20 is claimed is:—

1. In a device of the class described, body members; a tread extended across the joint between the body members; splice bars applied to opposite sides of the body members 25 and extended across the joint between the body members, one of the splice bars being engaged with the body members only, and the other splice bar being engaged with the body members and with the tread, both splice bars being provided with elements en-

gaged beneath the body members; means for connecting said elements below the body members; grip bars applied to one side of the body members, between adjacent splice bars; and means for connecting the grip bars with the body members; the lateral edges of the body members being engaged by the splice bars only.

2. In a device of the class described, body members; a tread resting upon the body 40 members and extended across the joint between the body members; splice bars applied to opposite faces of the body members, one splice bar being engaged with the body members only, and the other splice bar being engaged with the body members and the tread, both splice bars being extended beneath the body members; means for connecting the splice bars below the body members; and a grip bar applied to one side of 45 one body member and engaged with the tread and with said body member only.

Signed at Steelton, in the county of Dauphin and State of Pennsylvania, this 22 day of September 1911.

GEO. W. DRESS.
CHRISTIAN F. BECK.
